No. 678,697.

R. E. SCOTT.
END SILL FOR CARS.
(Application filed Mar. 9, 1901.)

Patented July 16, 1901.

(No Model.)

UNITED STATES PATENT OFFICE.

ROBERT E. SCOTT, OF FORT SCOTT, KANSAS.

END SILL FOR CARS.

SPECIFICATION forming part of Letters Patent No. 678,697, dated July 16, 1901.

Application filed March 9, 1901. Serial No. 50,468. (No model.)

To all whom it may concern:

Be it known that I, ROBERT E. SCOTT, residing at Fort Scott, in the county of Bourbon and State of Kansas, have invented a new and 5 Improved End Sill for Cars, of which the following is a specification.

My invention relates to improvements in that type of end sills constructed of pressed steel or malleable cast-iron; and it primarily 10 has for its purpose to provide an end-sill construction more particularly adapted for box or freight cars of a very simple and economical nature which when connected together in the manner hereinafter described forms a 15 very solid, rigid, and stable end sill, having suitable provisions for easily connecting the corner posts and braces to the sill and rigidly supporting them thereon.

My invention comprehends in its make up 20 a metal housing or cap adapted to be conveniently fitted upon the end of the sill, having a special arrangement of tongues or ribs and pockets to receive the end sill and having the front face suitably arranged to receive the 25 siding boards.

My invention in its specific nature consists in certain details of construction and peculiar combination of parts, all of which will hereinafter be fully described, and particularly 30 pointed out in the appended claims, reference being had to the accompanying drawings, in which—

Figure 1 is a perspective view of an end sill for box-cars constructed in accordance with 35 my invention. Fig. 2 is a cross-section of the sill, taken practically on the line 2 2 of Fig. 3. Fig. 3 is a horizontal section taken on the line 3 3 of Fig. 2. Fig. 4 is a view of a modification hereinafter referred to.

Referring now to the accompanying drawings, in which like characters indicate like parts in all the figures, 1 designates a metallic sill member which is substantially L-shaped in cross-section, the upper and 40 lower members 1^a 1^b of the same being extended forwardly of the front or vertical face 1^c and thickened to form strong outwardly-projecting horizontally-disposed flanges 1^d 1^d, whereby a suitable intervening space 1^e (in 45 practice about one inch deep) is produced to

receive wooden siding members, (indicated by 2,) the upper and lower edges of which are protected by the said flanges 1^d 1^d.

The ends 1^f of the housing 1 are closed, as shown in Fig. 3, and the said ends extend 55 back even with the top and bottom members, and the housing is of a height sufficiently greater than the height of the sill members A, which are supported thereby, so that the upper face of said housing will lie flush with 60 the decking B, as clearly shown in Fig. 2.

The housing 1 has a series of inwardly-extending partition members 2^a of suitable thickness—for example, three-eighths of an inch. Its members 2^a may extend backward 65 a distance less than that of either the top, bottom, or ends of the housing 1, or they may extend out as far as the said members, as shown, and the said partitions in practice are arranged closely together at the center or 70 draft sill part and are more widely separated at the ends of the housing, such arrangement being provided to give extra strength to the center of the housing, where it is most needed.

To further brace the housing 1 on the 75 ends of the sills A and to increase the strength thereby, the front wall 1^c is formed with an integral inwardly and horizontally disposed strengthening-rib 3, and the said ribs may extend but partially outward toward the inner end of the housing, as shown in Fig. 3, or they may extend flush with the inner end, as shown in Fig. 4, and while I prefer to use the strengthening-rib within each of the faces and the pockets the said ribs may be entirely 80 omitted without departing from my invention.

Each sill A has its lower edge recessed, as at A', to receive the bottom portion of the housing, which portion lies flush with the bottom of the sills A, and the ends of the said 85 sills A are recessed on their sides, whereby to provide tenons to fit within the pockets, each of the said sills being also horizontally slotted to fit over the strengthening-ribs 3 when the said ribs are used.

The height of the housing 1 is slightly 95 greater than that of the sills, whereby to permit the insertion of a wooden or metallic wedge-piece C between the top of the housing and that of the sill, whereby to tightly 100

clamp the housing upon the end of the sill and also to provide a tongue-and-groove lock C for the adjacent decking-piece B.

5 D designates the truss-rods that extend from one end sill to the other in the usual manner.

The housing 1 at the corners is formed with angle-openings 5, having at the top vertically-projecting flanges, said housing having similar openings 5 in the bottom thereof, when so desired, to receive the corner-posts and brace members X' Y, and at a point midway of the corner-openings other openings 6 are provided to receive the center stay-
15 posts Z.

1^x indicates what I term the "grain-strip," which is in the nature of an angle-flange which extends vertically from the outer edge of the housing, as shown in Fig. 2, the said 20 grain-strip being so arranged as to leave the top of the sill in practice about two and one-half inches from the siding.

The housing member in practice is also formed with suitable pendent portions to receive the eyebolt or other connections for the brake-hanger, said parts being not shown, as they may be of any well-known construction.

From the foregoing, taken in connection 30 with the accompanying drawings, it is thought the manner in which my invention is practically applied and the advantages thereof will be readily understood by those skilled in the art to which it appertains. The same 35 provides a very simple, strong, and durable construction capable of being easily assembled in position for use, and should the metal housing in case of a collision become broken it can be easily removed and a new one substituted.

Slight changes in the details of construction may be made without departing from the scope of the appended claims, and it will be well understood that the parts thereof may be 45 modified to suit different styles of cars.

Having thus described my invention, what I claim, and desire to secure by Letters Patent, is—

1. An end-sill housing, comprising a metal 50 body L-shaped in cross-section, having closed ends, integrally-formed post and brace

receiving sockets, and having a series of transverse partitions, whereby to form pockets in its rear face, for the purposes specified.

2. A metal end-sill housing, having closed 55 front top, bottom and end portions, a series of rearwardly integrally-formed partitions, a central horizontally-disposed strengthening-rib, and integral sockets to receive the brace and end posts, for the purposes de- 60 scribed.

3. The combination with the sills A, of a housing 1, for the ends of the sills L-shaped in cross-section and adapted to slide upon the outer end of the sills A, said housing being 65 of a greater height than the said sills, and having a series of rearwardly-extending partitions, wedges detachably fitting between the upper end of the housing and the sills A, said wedges having shouldered offsets, and the decking-boards, and means for trussing and bolting the several parts together, all being arranged substantially as shown and for the purposes described.

4. An end sill, consisting of a L-shaped 75 body closed at the ends, said body having a series of rearwardly-extending division-plates, forwardly-projecting top and bottom flanges and post and brace receiving sockets, in the front face, for the purposes described.

5. The herein-described improvement in end sills for cars, comprising in combination with the sills A, having the sides and bottom of their front end reduced, and said end mortised in a longitudinal and horizontal direction, the housing 1, L-shaped in cross-section, said housing having closed ends, rearwardly-extending partitions, extending flush with the rear edges of the end members, said housing being of a height greater than 90 the sills A, said housing also having a horizontal strengthening-rib, forwardly-extending upper and lower flanges 1⁴, post-receiving sockets on the front face, and the angle-strip, forming an integral part of the housing, the wedge-blocks C, and the decking-boards B, all being arranged substantially as 95 shown and described.

ROBERT E. SCOTT.
